UNITED STATES PATENT OFFICE.

CHARLES E. GLESSNER, OF LINNONT, OREGON, ASSIGNEE OF ONE-HALF TO JOHN C. JONES, OF PORTLAND, OREGON.

ТИЛТИНГ FLOOR-SECTION.

1,144,651.

Specification of Letters Patent. Patented June 29, 1915.

Application filed April 23, 1913. Serial No. 763,075.

To all whom it may concern:

Be it known that I, CHARLES E. GLESSNER, a citizen of the United States, residing at Linnont, in the county of Multnomah and State of Oregon, have invented certain new and useful Improvements in Tilting Floor-Sections, of which the following is a specification:

This invention relates to tilting floor sections; and has for its object to provide a floor composed of sections pivotally mounted in such manner that they may be united together to form a continuous floor surface, which sections may be tilted to bring different faces uppermost.

A further object is to provide such sections which may be tilted upon their pivots to swing their upper faces into a different plane where they will again be united to form a continuous floor.

A still further object is to provide a plurality of floor sections which are polygonal in cross section and which are pivoted to rotate upon their longitudinal axes, so that corresponding faces of said sections may be brought to form a continuous floor; and further that each of said floors may be formed upon a different plane.

I accomplish these and other objects by the mechanism illustrated in the accompanying drawing, in which—

Figure 1 is a transverse sectional view of the floor sections united to form a horizontal floor, taken on the line A—B of Fig. 3 and represented as a straight line. Fig. 2 is a longitudinal sectional view taken on the line C—D of Fig. 3 showing the main floor, with a section in place; and a balcony to which the sections may be united. Fig. 3 is a plan of a floor embodying my invention. Fig. 4 is a detail of a worm gear mechanism for tilting the sections upon their pivots, and showing the eccentrically mounted end. Fig. 5 is a diagrammatic view representing the manner of determining the position of the eccentric bearing.

Referring to the drawing in detail, 1 represents the horizontal face of each of the floor sections, which are triangular in cross section, and which are united together, to form the body of a floor for an auditorium, extending from the balcony front 2 to the horizontal rostrum 7. The horizontal floor, it will be noted, has an outer circular section 3 corresponding to the balcony.

The fixed portion 3 of the horizontal floor, which encompasses the tilting sections is provided beneath its inner edge with a series of columns or supports 6^a, disposed at suitable intervals, and in which is mounted, upon a trunnion 4, each of said sections 1. The rostrum, it will be understood, is provided with a series of bearings 8; which rest upon a column or abutment 6^b, and in each of them is mounted on a suitable bearing 9 one of said sections. These mountings form an axis of rotation which is parallel to one face of the section while the other face is longitudinally inclined thereto.

As seen in Fig. 4, the bearing is fixed in the center of the larger triangular end, thereby permitting the smaller end of the section which is centrally mounted to rotate thereon in a manner to bring either of its faces flush with the rostrum floor. The outer and larger end is mounted eccentrically, upon the bearing 4, at a point adjacent the face 1 of the fixed portion of the main floor, and at a previously determined point with reference to the lateral edges of the faces, so that when the section is tilted through an angle of 120 degrees, it will carry the face 1^b to the plane of the balcony 2 to which it will be united to form a continuous floor leading to the rostrum as indicated at 1^a.

In Fig. 5 is illustrated the manner of determining the location of this bearing. Let abc represent an equilateral triangle whose upper line ab lies in the plane of the balcony, and line a'b' parallel therewith represents a continuation of the main floor 3 and the distance between said lines will represent the vertical distance between the main floor and the balcony, taken at random. Then bisecting the angle b'a'c we get the line d'o on which the pivot is to be located. To determine the point of that pivot, locate the point x on the floor line 3 in the vertical plane of the point a. Then draw a line through the points x and c, and a line e bisecting that line at right angles will intersect the line a'o at the desired point for the pivot 4, which will be determined by the arcs f drawn from x and c respectively as a center. Swinging the triangle abc on the pivot 4, through an arc of 120 degrees it will assume the position yzx, with the line ac taking the position of yx, which corresponds to the horizontal face of the sec-

tions in Fig. 1, thus bringing the body of the floor, represented by these floor sections, from the plane of the balcony to the plane of the main floor.

5 The horizontal face of each section carries a counterpoise 4^a made preferably of concrete to counterbalance the weight of the inclined floor face 1^b and which acts as a reinforcement; and when face 1 is in use, 10 the lugs 5^a will swing against the abutment 6, to which it is secured by means of bolts 5, or any suitable means. When the sections are rotated on their pivots so as to bring the face 1^b into line 1^a with the balcony, the edge portion 13 will engage the opposite face of the abutment to which it may be secured in a similar manner.

To operate the sections a gear 10 will be secured upon one of the pivot shafts, as 9, 20 and a worm gear 14 having a crank 11 is mounted upon a support 12 to mesh therewith, and by means of which the section may be tilted upon its pivots through an arc of 120 degrees so as to bring it in to line 25 with either of said floors. It is obvious that opera chairs may be fixed in regular order upon the face 1^b, so that when the sections are adjusted to the balcony a continuous seated auditorium is provided, and by swinging the sections down, a horizontal hall 30 floor is provided. In this manner I have provided a series of tiltable floor sections which are shaped substantially as the frustum of a triangular pyramid, which sections are adapted to fit neatly upon each other and which unite in a neat joint with the rostrum and with the adjacent fixed floor, thereby forming a circular floor.

It will be observed that one of the faces of 40 the triangular sections is not here used as a floor face, but that the structure is so shaped and modified as to rest upon the abutment 6.

The floor plan of Fig. 3 shows a fixed 45 portion at each side with the tilting sections mounted intermediately. The floor may be formed upon a complete circle or any portion thereof. A fixed balcony with its floor 2, and rail 2^a will be made in conformity to 50 the fixed horizontal floor. It is obvious, however, that in case a circular building is constructed there will be no fixed lateral portions.

In adjusting the sections from the horizontal to the inclined position, the sections 55 should be so moved that each one will immediately follow the movement of the preceding section, so that as the preceding section swings from its normal position it gives 60 room for the next section to swing on its axis; and they will all, thus successively move into place, in either direction.

As shown in Fig. 1 only a portion of a 65 circle being used, there is a fixed wall at the initial point, which makes it necessary

to narrow the upper face of the first section, so that it may swing by the fixed portions of the structure.

Having now described my invention what I claim is—

1. A tiltable floor section having a plurality of floor faces, bearings formed at an incline with reference to one of said faces, and means for tilting the section to bring said faces into their respective floor lines. 75

2. The combination in a building having a main partial floor and a second partial floor fixed above said main partial floor, of a tiltable section having a plurality of faces each adapted to form a section in one of 80 said partial floors, and means for tilting said section to bring each of its faces into the plane of its corresponding partial floor.

3. The combination in a building having a main floor about its outer portion and a 85 balcony conforming thereto, above it, of a floor section having a plurality of longitudinal faces each adapted to form a section in one of said floors, mounted at an intermediate point in said building, and means 90 for tilting said section whereby one of its faces will be brought into the plane of its corresponding floor.

4. A floor section having substantially the shape of the frustum of a triangular pyramid, means for tilting the section on its supports to bring either face uppermost and varying the plane of each face as it comes 95 into the floor line.

5. A floor comprising a plurality of sections, each having substantially the shape of the frustum of a triangular pyramid, means for tilting the sections on their supports to bring corresponding faces thereof into the floor line and varying the relative 105 plane of each face as it comes into the floor line.

6. The combination in a circular building having an inclined balcony floor and a corresponding horizontal main floor with an 110 intermediate portion comprising a plurality of sections each having substantially the shape of the frustum of a triangular pyramid and each fitting neatly upon the other and upon the contiguous end portions of 115 the floor, each section being mounted eccentrically at the rear end with one face in line with the main floor and another face adapted to be swung into line with the balcony floor, and the other end mounted centrally, and means for swinging the sections 120 on their bearings.

7. The combination in a circular building having an inclined balcony floor and a corresponding horizontal main floor with an 125 intermediate portion comprising a plurality of sections each having substantially the shape of the frustum of a triangular pyramid and each fitting neatly upon the other and upon the contiguous end portions of the 130

floor, each section being mounted eccentrically at the rear end with one face in line with the main floor and another face adapted to be swung into line with the balcony floor, and the other end mounted centrally, means for swinging the sections on their bearings and a longitudinal support positioned centrally beneath each section.

8. The combination in a circular building having an inclined balcony floor and a corresponding horizontal main floor with an intermediate portion comprising a plurality of sections each having substantially the shape of the frustum of a triangular pyramid and each fitting neatly upon the other and upon the contiguous end portions of

the floor, each section being mounted eccentrically at the rear end with one face in line with the main floor and another face adapted to be swung into line with the balcony floor, and the other end mounted centrally, means for swinging the sections on their bearings, a counterpoise to balance each section, and means for securing each section in position.

In testimony whereof I affix my signature in presence of two witnesses.

CHARLES E. GLESSNER.
